FRANCIS W. KEEGAN, OF NEW YORK, N. Y.

MIXING DEVICE

Application filed January 16, 1925. Serial No. 2,770.

This invention relates to internal combustion engines, and my present improvements pertain to stationary means situated in the passage which communicates from the 5 throttle to the intake manifold, adapted to so direct the flow of fuel mixture through said passage that the stream of fuel mixture will first be divided, then caused to impinge on passage surfaces tending to break up the 10 fuel particles, besides setting up a turbulent condition in the mixture, and then the divided stream is reunited by convergence and consequent impaction, under whose influence the fuel particles become further com- 15 minuted.

My invention is based on the principle that at low engine speeds, when the velocity of the flowing fuel mixture is insufficient to bring about atomization of the fuel, the fuel 20 mixture passage is to be heated as by the application of heat from the exhaust, (see my pending application, Serial No. 742,763, filed October 10, 1924) and when the velocity of the flowing mixture increases upon opening 25 up the throttle, then the heating means is cut off and the larger volume of the fuel mixture stream, flowing at a higher velocity, is caused by impaction of the fuel particles, the stream being first divided and then brought 30 together, to break up said particles into finer divisions, thus providing efficient atomization without the loss in weight of the fuel mixture charge that occurs with vaporization by heat.

With this premise my invention consists of 35 certain control means for the flowing fuel mixture, located in the passage communicating from the carburetor, and the throttle, to the intake manifold, these control means 40 being adapted to assure a constant, proportionate pull upon the fuel nozzle, at the varying engine speeds and according to the volume and flow velocity of the aspirated air, without permitting an excess supply of fuel 45 to be drawn from the nozzle at full open throttle.

In accomplishing this object I depend more upon the pull force exerted by the vacuum in the manifold to extract the fuel from the 50 nozzle, and I make the Venturi tube which

surrounds the nozzle of generous area so that no strangling effect is provided at that point to too greatly enrich the mixture as the air flow velocity increases through said Venturi tube. Instead another Venturi tube is 55 provided in the fuel mixture passage, above the carburetor nozzle and its Venturi tube, and above the throttle valve, this other Venturi tube communicating with my improved fuel mixture control means. The control 60 means are provided in and by an enlargement of the fuel mixture passage, and include a central cone which has the effect of dividing the stream so that it diverges from below and then converges above, to reunite. Also 65 the central cone has an axial orifice through which a limited quantity of the flowing stream passes. This orifice has Venturi contour, so that mixture passing therethrough diverges upon exit and intersects the re- 70 entrant or converging stream flowing outside the cone.

The enlargement of the fuel mixture passage forming part of my improved control means, is jacketed and heated with gases from 75 the exhaust, and the cone referred to is hollow and adapted to receive part of these exhaust gases, so that the main flowing stream of fuel mixture may have heat applied thereto both inside and outside, and the stream passing through the axial orifice in the cone may 80 have heat applied directly thereto.

Further, I provide a Venturi tube above the point where the divided stream parts are caused to meet, and anterior to said last named 85 Venturi tube the passage enlargement is shaped like an annular shoulder, to retard direct upward flow of the fuel mixture and set up therein a turbulent effect, thereby accentuating the degree of atomization which results as the divided parts of the stream re-unite.

Other features and advantages of my invention will hereinafter appear.

In the drawing:—

Figure 1 is a side sectional view showing my improved control device located in the passage between the carburetor and intake manifold of an internal combustion engine.

Fig. 2 is a top plan view of the control device, and

Fig. 3 is a partial detail view of a modification.

5 In said drawings let 1 indicate a carburetor, having fuel nozzle 2, Venturi tube 3, here shown as of larger than usual diameter, a throttle valve 4, and the flange 5 by which a carburetor is usually connected to an intake manifold. In this instance however, the flange 5 is shown as attached to the lower, open end of a hollow casing or jacket 6, which contains, in spaced relation, a cylindrical shell 7, that is in effect an enlargement of the 10 fuel mixture passage between the carburetor pipe 8 and intake manifold pipe 9.

The jacket 6 is attached by its upper flange 5^a to the manifold flange 10.

20 The shell 7 is reduced in diameter toward its upper end, thereby forming an annular shoulder 11, which is surmounted by a continuing Venturi tube 12, that leads directly into the manifold pipe 9.

25 Fitted within the shell 7 at its lower portion is a Venturi tube 13, here shown as having a base flange 14, seated upon a ring 15, lying between said flange 14 and the carburetor flange 5. Also an annular skirt 16 depends from the upper perimeter of the Venturi tube 30 13, in spaced relation both with the wall of said Venturi tube and with the shell 7, thereby providing the respective clearances 17 and 18; the lower end of skirt 16 being flared outwardly, at 19, to fit against the shell 7, in spaced relation to flange 14.

35 Located centrally within the shell 7, in intermediate, spaced relation to the Venturi tubes 12 and 13, is a circular deflector 20, provided with a central orifice 21 of Venturi contour. Externally the deflector is a double cone, in appearance being somewhat pear-shaped, except that its lower surface portion 22 is concaved, and its upper surface portion 23 is convexed.

40 The deflector is here shown as supported by means of arms 24 which connect it with the inner surface of Venturi tube 13.

45 The space between shell 7 and the central device 20 provides the main passageway for fuel mixture, in concentric relation to the central Venturi orifice 21.

50 The stream of fuel mixture entering the control device through Venturi tube 13 is therefore drawn upwardly in part through Venturi tube 21 and in part around the device 20.

55 Since the greatest velocity of a flowing stream is at its centre it follows that when less than a full volume of mixture is traversing the passage, the highest speed attained will be through the Venturi tube 21, and the larger portion of the stream, divided by cone 20, will have a relatively slower flow rate. Therefore, 60 when the throttle is only partly open the flow

rate of mixture through Venturi tube 21 will be greater than the flow rate outside cone 20. But the injector action of the jet issuing from Venturi tube 21 will have the effect of siphoning the volume of mixture moving more slowly outside cone 20, tending to draw the lighter fuel particles thereof sharply into impaction with the central jet.

70 When the flow velocity of the fuel mixture is low, as at idling speeds, or with the throttle valve only partly open, then heat is to be applied to the flowing fuel mixture to vaporize the fuel. For this purpose exhaust gases enter jacket 6 by way of a pipe 25, leading from exhaust manifold 26, to pass through the space 27 between the jacket 6 and shell 7 and having their exit through a pipe 28 into the exhaust pipe 29. By automatic control means such as are described in my co-pending application No. 742,763, previously referred to, the application of exhaust heat is cut off when the throttle valve is opened more widely, because then the fuel is to be gasified as a dynamic function of directional means causing the fuel particles to become smashed by impaction.

75 The deflector or cone 20 is hollow, being provided with the interior space 30, and its supporting arms 24 are also hollow, to provide means of communication between space 30 and the space 17. Since the space 17 is also in communication with space 27 by means of openings 31 through shell 7, it follows that some of the exhaust gases are enabled to pass through the cone or deflector, thereby heating its surfaces which are exposed to the flowing mixture both through the Venturi tube 21 and the main passage-way 32.

80 With the increase in flowing volume of the fuel mixture due to a widely open throttle and its higher velocity as the engine speed rises, the flow through Venturi tube 21 reaching its maximum volume, the larger volume which is divided by and passes around central device 20 acquires dynamic energy which is utilized for atomization purposes.

85 The divided stream strikes against the concaved surface 22, tending to break up the fuel particles; it is thence deflected to the surface of shell 7, turbulence and further comminution resulting through the angle of deflection taken by the mixture and its intersection with outwardly ascending portions of the stream.

90 The path of the flow takes the divided stream around the convexed surface 23, toward the entrance of Venturi tube 12. In the course of this travel these effects are achieved; the outward portion of the stream strikes against an overhang 11 or upper constricted portion of the shell 7, just anterior to the entrance of Venturi tube 12, said overhang having an upward curve that merges into said Venturi tube, and said overhang and Venturi tube entrance, besides forming an impaction

abutment, for further comminution of the fuel particles, also causing a rolling action to be given the stream which sets up a turbulent condition therein, and then the divided 5 portions of the stream reunite under dynamic impact and intersect the central portion of the stream issuing from Venturi tube 21, also with impact force, all tending to a thorough atomization of the fuel and perfect mingling of the air and fuel.

10 When the throttle is widely open and depression in the manifold increases to a point where the volumetric capacity of the fuel mixture passage is satisfied, then the volume 15 of the stream portion outside deflector 20 will exceed the volume through Venturi tube 21, because of the larger area of the space 32 between deflector 20 and shell 7, and then the atomizing effects by impact of fuel particles, previously referred to, will be most 20 efficiently achieved.

In the modification of Fig. 3 the flow retardation effect from the passage-way 32 into Venturi tube 12, is enhanced by increasing 25 the height of shell 7 relatively to the entrance to said Venturi tube, thereby creating an annular pocket 33 into which the ascending heavier particles of fuel will become lodged, especially when the flow velocity is low, until 30 vaporized under the influence of the applied heat.

It should also be noted that at low motor speeds, as when idling, the arms 24 which support cone 20, have the effect of causing 35 fuel mixture which flows outside the cone, carrying its heavier fuel particles against the exit mouth of Venturi tube 13, to take a gyratory path in passage-way 32, between the flare or base 19 and the top 11 thereof, whereby fuel particles are caught against the surface 40 of shell 7. As the shell 7 is hot some of this fuel becomes vaporized and passes into the upwardly flowing stream, but heavier particles of fuel in the gyrating mixture cling 45 to the surface of shell 7 and in their upward travel become arrested by the overhang at 11.

When the flow velocity is very low the heavier fuel particles ascending against the surface of Venturi tube 13 to its exit edge will 50 gravitate into the trough 34 formed between skirt 16 and shell 7. Constant dispersion of this collected fuel occurs while the engine speed is low, because heat is applied at that time, causing the fuel therein to vaporize and 55 mingle with the pocketed air, which carries it into the stream. Inclined studs 35 extended between the flange 19 and the Venturi tube 13 are pierced with very small orifices 36 that 60 communicate from the trough 34 to the interior of said Venturi tube, to serve as drains for carrying off any liquid fuel which may remain in said trough when the motor is stopped.

65 Variations within the spirit and scope of

my invention are equally comprehended by the foregoing disclosure.

I claim:

1. A mixing device adapted to be connected between a carbureter and manifold, comprising a shell, a deflector for dividing the flow of fuel mixture and arranged in spaced relation to said shell to define a passageway, said shell being jacketed and adapted to be heated by the passage of hot exhaust gases between said shell and jacket, the lower portion of said deflector presenting an annular concaved surface to the ascending fuel mixture and said shell having a hollow interior, and means of communication between said hollow interior and the jacketed area occupied by the hot exhaust gases. 70

2. A mixing device adapted to be connected between a carbureter and manifold, comprising a casing, a shell arranged within said casing and spaced therefrom to define a passage for the flow of hot exhaust gases, a deflector for dividing the flow of the fuel mixture and disposed centrally of said shell to define a passageway, a Venturi tube positioned below said deflector and forming the entrance to said passageway and an annular skirt surrounding said Venturi tube, said skirt co-acting with said passageway to provide a trough exteriorly of said Venturi tube to collect fuel gravitating therein after passing up said Venturi tube and said skirt also providing a space surrounding said Venturi tube in communication with the passage containing the flowing hot exhaust gases. 80

3. A mixing device adapted to be connected between a carbureter and manifold, comprising a casing, a shell arranged within said casing and spaced therefrom to define a passage for the flow of hot exhaust gases, a deflector for dividing the flow of fuel mixture and disposed centrally of said shell to define a passageway, a Venturi tube positioned below said deflector and forming the entrance to said passageway and an annular skirt surrounding said Venturi tube, said skirt co-acting with said passageway to provide a trough exteriorly of said Venturi tube to collect fuel gravitating therein after passing up said tube and said skirt also providing a space surrounding said tube in communication with the passage containing the flowing hot exhaust gases and said trough having orifices for draining the collected fuel to said Venturi tube. 90

4. A mixing device adapted to be connected between a carbureter and a manifold, said device comprising a shell and a deflector arranged in concentric relation within said shell, said deflector having an axial Venturi-like orifice for the passage of the central column of the flowing mixture, and said deflector serving to define a passage-way with said shell, said deflector also having an intermediate enlarged portion positioned within the 100

110

120

125

130

shell, said enlarged portion presenting at its under side an annular concaved impact surface to the ascending fuel mixture, and said enlarged portion co-acting with the shell to form a succession of angular impact surfaces to aid in breaking up the fuel particles.

5. A mixing device adapted to be connected between a carburetor and a manifold, said device comprising a shell and a deflector for dividing the flow of fuel mixture, said deflector arranged in spaced relation within said shell to define a passage-way therewith, the upper portion of said shell presenting an annular overhang surface in the path of the ascending fuel mixture, and a Venturi tube located above said deflector to convey the fuel mixture to the manifold, said annular overhang surface having a convex formation that merges into said Venturi tube.
